UNITED STATES PATENT OFFICE

JACOB BALDNER AND GEORGE BALDNER, OF XENIA, OHIO; SAID GEORGE BALDNER AS-
SIGNOR OF HIS ENTIRE RIGHT TO KENNETH S. CLAPP, OF CLEVELAND, OHIO

GREASE DISPENSER

Application filed May 15, 1922, Serial No. 561,080. Renewed December 3, 1930.

Our invention relates to dispensing apparatus for plastic and semi-fluid materials, more particularly to an apparatus for discharging greases, oils, paste or heavy or 5 viscous fluid in measured quantity.

The present application is a continuation in part our pending applications for Letters Patent Serial No. 453,978 filed March 21, 1921, and Serial No. 475,637, filed June 7, 10 1921.

The invention forming the subject matter hereof contemplates motor driven apparatus for feeding the material to be dispensed from a reservoir or container through an extended 15 hose or discharge conduit, having means at the nozzle end thereof, for initiating periodic operation of the device, with a meter or timer mechanism for arresting the operation of the apparatus at the expiration of the operative 20 period, when a predetermined quantity of the commodity has been discharged, with further provision for insuring uniform discharge of the commodity during such period of operation, by eliminating air pockets in the body 25 of the discharged commodity, and preventing back leakage in the feeding mechanism.

The object of the invention is to simplify the structure as well as the means and mode 30 of operation of such apparatus, whereby it will not only be cheapened in construction, but will be more efficient in use, positive in operation, uniform in action, accurate and unlikely to get out of repair.

A further object of the invention is to provide "a one man" apparatus, whereby a single 35 operator in charge of the discharge nozzle, at a remote point from the supply reservoir and feeding apparatus, may control such apparatus, without necessitating a second operator for manipulating the dispensing mechanism. The structure is particularly applicable for feeding lubricant or grease in a 40 garage for filling transmission and differential casings of motor vehicles. With the type 45 of apparatus now in common use, one operator is required to operate the pump or dispensing means, while a second operator holds the nozzle of the discharge hose or conduit in the supply orifice of the transmission or differential casing, and signals the pump oper-

ator when grease is to be supplied or its supply arrested. The present invention is designed to place the entire operation under control of a single operator who is in charge 55 of the supply nozzle.

A further object of the invention is to provide an improved regulator or timer for the motor driven apparatus, by which the motor will be automatically disconnected after a predetermined period of operation necessary 60 to dispense a measured quantity of the commodity. This timer involves an automatically driven circuit breaker which will interrupt the motor circuit with minimum arcing, 65 with means for again setting it in operation from a distant point.

A further object of the invention is to provide adjustable means by which the extent of the periodic operation may be varied to accommodate the apparatus to feeding commodities of different consistencies or 70 different character.

A further object of the invention is to provide an improved form of auxiliary pump or booster with means for preventing any yielding or leakage under influence of back pressure, thereby insuring the delivery of a full 75 measured quantity at each operative period.

A further object of the invention is to provide improved screw feed dispensing means 80 of such character and capacity in relation with the discharge capacity of the apparatus, as to effectively prevent the forming of air pockets and the assurance of the delivery of 85 a continuous and solid stream of dispensed commodity.

With the above primary and other incidental objects in view as will more fully appear in the specification, the invention consists 90 of the features of construction, the parts and combinations thereof, and the mode of operation, or their equivalents as hereinafter described and set forth in the claims.

In the accompanying drawings, wherein is 95 shown the preferred, but obviously not necessarily the only embodiment of the invention, Fig. 1 is a side elevation, partly broken away, of the assembled apparatus forming 100 the subject matter hereof.

Fig. 2 is an elevation viewed from the left of Fig. 1.

Fig. 3 is a top plan view and

Fig. 4 a sectional plan view of the assembled apparatus.

Fig. 5 is a diagrammatic view illustrating the electric control circuit for the driving motor.

Fig. 6 is a vertical sectional view and

Fig. 7 a top plan view of the timer or regulator by which the period of operation required for discharging a measured quantity of the commodity is determined.

Fig. 8 is a side elevation of the booster or pump utilized in the present instance as a meter, one head of the meter casing being removed.

Fig. 9 is an interior side elevation of the head of the meter casing removed from the meter shown in Fig. 8.

Fig. 10 is a vertical sectional view substantially on line 10—10 of Fig. 8.

Fig. 11 is a sectional view of the housing.

Fig. 12 is a sectional view of the hose or conduit showing embedded therein the circuit wires for the electric control.

Like parts are indicated by similar characters of reference throughout the several views.

Referring to the drawings of the preferred embodiment of the invention, 1 is the container or reservoir for the material to be dispensed in measured quantity. This reservoir or container rests upon a base 2, within which is contained the ejecting apparatus.

The base or housing 2 is provided with an open pocket or chamber 4, with which the open bottom of the reservoir or container 1 registers. Within the bottom of the chamber

40 or pocket 4 of the base 2, there are formed a plurality of parallel semi-circular grooves or recesses 5, terminating at one side of the chamber 4 in concentric bores or circular passages 6, which form continuations of the

45 grooves 5, in the base or housing 2, and which extend beyond the chamber or receiving pocket 4. Located in each of the semi-circular grooves 5 and extending thence into the corresponding bore or passage 6, is a revolu-

50 ble spiral conveyor 7. There may be any number of these spiral conveyors in the series. In the drawings, but four have been shown.

It is obvious that more or less number of such conveyors may be employed. The conveyors

55 extend a sufficient distance through the passages or bore 6 to afford ample bearing therein, for one end of the conveyor screw, while at their opposite ends, they are provided with suitable bearings in the wall of the chamber 4 and are furthermore interconnected one with the other, for rotation in unison by intermeshing gear pinions 10.

As shown in the drawings, the pitch of the succeeding conveyor screws is reversed, and these conveyors are rotated in reverse direc-

tion by the intermeshing gear pinions 10, whereby the conveyors simultaneously advance the plastic or semi-fluid materials uniformly in the same direction, that is to say, toward the bores 6, through which the commodity is discharged from the chamber 4. In practice, the rotation of these screws, one toward the other, forms intermediate the conveyors of each pair, a ridge of material, which is uniformly advanced toward the discharge ends of the conveyors within the bores 6, as the conveyors are rotated. It will be noted in Fig. 4, that the pitch of the conveyor screws is not uniform, but gradually decreases as it approaches the discharge end of the conveyor screw. This variable pitch conveyor facilitates the gathering of the commodity from the distant side of the container or reservoir, advancing it toward the discharge outlet, where it is subject to gradually increasing pressure, as the rate of speed across the chamber 4 decreases.

The trunnion shaft of one of the conveyor screws extends beyond the chamber 4, as indicated at 11, to afford a driving connection for the series of conveyor screws, 7. These conveyor screws 7 may be manually operated by means of a hand crank shown by dotted lines at the top in Fig. 2, but are preferably motor driven by an electric motor.

As shown in Figs. 1 and 2, the shaft extension 11, of the initial screw conveyor of the series is provided with a bevel gear pinion 12, meshing with a like pinion 13 upon a vertically disposed power shaft 14. The drive shaft or power shaft 14, carries a worm wheel 15, with which meshes a driving worm upon the armature shaft of an electric motor 17. Upon the operation of the driving motor 17, the spiral conveyors 7 are simultaneously actuated through the influence of the worm 16, meshing with the worm wheel 15 upon the power shaft 14, and interconnecting pinions 12 and 13 to discharge the commodity from the container or reservoir 1, through the lateral bores 6 of the base 2, into a pressure chamber 18, formed at one end of the base or housing 2. The bores or passages 6 all communicate with this pressure chamber, and simultaneously discharge thereinto.

To provide for hand manipulation in the event of an emergency, or for use under abnormal conditions, the upper end of the power shaft 14 is provided with a bevel pinion 19, meshing with a similar gear upon a transverse shaft 20, to which may be connected a detachable hand crank 21, for hand actuation of the apparatus. To permit such operation independent of the motor 17, the worm wheel 15 is preferably though not necessarily connected to the power shaft 14, by means of a pawl and ratchet connection, shown at 22, whereby the power shaft 14 may be rotated in an advance or forward direction by means of the hand crank, independent

of the worm wheel 15, during which advance movement, the pawl will ride idly, over the teeth of the ratchet wheel. However, upon operation of the motor and consequent rotation of the worm wheel 15, the pawl carried by such worm wheel will operatively engage the ratchet wheel which is fixedly secured upon the power shaft to drive the power shaft in unison. Such pawl and ratchet connection is shown for illustrative purposes only. It being obvious that any suitable form of engaging clutch mechanism may be substituted therefor.

Leading from the pressure chamber 18 of the base or housing 2, is a discharge conduit comprising preferably a flexible hose 23 of such character as to withstand the high pressure under which the commodity is delivered. There are upon the market at the present time, various forms of metallic flexible hose and metal bound or armored hose, which are suitable for this purpose. Located at the outlet of the pressure chamber 18 to the hose connection 23 is a rotary power driven meter 24, comprising a cylindrical housing 25, having inlet and outlet passages 26 and 27. Mounted eccentrically within the circular housing 25, is a rotor 28, having therein two oppositely disposed overlapping sliding blades or vanes 29. These vanes are slotted or formed with registering recesses in their inner or overlapping portions to receive springs 30 by which the blades or vanes are forced apart, and against the wall of the housing 25 as the rotor 28 revolves. During the rotation of the rotor, the blades or vanes reciprocate to and fro therethrough, due to the eccentricity of the wall of the housing 25, and the axis of rotation of the rotor. The blades or vanes maintain, at all times, their bearing contact upon the interior walls of the cylinder under the influence of the springs 30.

The rotor 28 is positively driven by means of a bevel gear 31, upon the rotor shaft, which intermeshes with a similar gear 32, upon an extended stem or shaft of one of the spiral conveyors 7, which projects through the pressure chamber 18, and through a suitable stuffing box, 33A, to support on its outer end, the said gear pinion, 32. The rotary meter is thus positively driven in unison with the actuation of the spiral conveyors 7. The capacity of the spiral conveyors 7 is very much greater than the capacity of the meter, through which the discharged commodity must pass. The result of this preponderance of feeding capacity of the conveyor is to maintain a supply of commodity under pressure within the chamber 18. The conveyors feed the commodity to the chamber 18 very much faster than the meter, will permit it to discharge therefrom. The result is that the surplus material is squeezed back, along the spirals of the conveyors 7, but the chamber 18 is always maintained filled to its en-

tire capacity. One of the purposes of this oversupply of commodity to the chamber 18, in quantities greater than is permitted to escape through the meter, is to insure the avoidance of air pockets and to assure a continuous discharge of uniform density. Any entrapped air is permitted to escape rearwardly through the bore 6 with the surplus material, which is squeezed backwardly or overflows the spiral flute of the conveyor. Without some such provision, the feeding of the commodity would be spasmodic and the discharged material would be inclined to splutter due to the expansion of small pockets of compressed air as the material leaves the discharge nozzle. Moreover, there would be no assurance of full measured quantity. The quantity discharged would vary as part of the bulk would be compensated for by such pockets of air. Moreover, in such case the entrapped or entrained pockets of air would conduce varying density of the material at different points in the discharge.

By providing the feeding apparatus and the meter in tandem relation, but with different capacities whereby the meter is supplied with a quantity of commodity greater than its capacity to measure, a full charge to the meter is insured at each rotation, and the density of the successive charges will be uniform.

In order to prevent back leakage, through the meter, or any slight variation of the blades or vanes of the meter rotor, due to back pressure within the discharge conduit 23, means is provided for advancing the blades or vanes into close operative contact with the walls of the meter casing 25, during the operative stroke of such blades or vanes. This positive actuating means for the meter blade operates entirely independent of the spring 30. It consists of notches or grooves 33 formed in the ends of the vanes or blades 29, which engage over cam beads or flanges 33', projecting inwardly from the heads of the meter casing 25. The construction is such that as the blade 29 approaches its operative position or point of greatest stress, that is to say, as it passes the inlet orifice 26, the notch or groove 33 rides over the flange or bead 33', which is arranged in such concentric relation with the path of travel of the blade or vane, that it will serve to maintain the blade in operative bearing relation with the circular wall of the meter casing 25. The ends of the retaining bead or flange 33' are beveled or reduced somewhat in thickness to afford a camming action and facilitate the engagement and disengagement of the blade, 29. The flange or bead 33' is of such length that it maintains the meter blade or vane against retraction under excessive back pressure, throughout its operative stroke from the inlet orifice 26 to the outlet orifice 27. It will be obvious that as the rotor 28 advances, the

space intermediate the rotor 28 and wall of the meter casing immediately in the rear of the blade or vane 29 will be filled with the commodity under pressure of the feeding screws 7. This space will continue to receive such commodity until the blade approaches the outlet orifice 27, at which time the opposite blade 29 is in position to pass the intake orifice 26, and by its advance force the charge received within the casing 25, forwardly toward the outlet 27. At each operation this charged space is completely filled under uniform pressure. The charge capacity of this space being known, a predetermined quantity of the commodity may be delivered by limiting the operation of the meter to a predetermined number of rotations of the rotor.

In order to regulate the discharge of commodity by limiting the periodic operation of the apparatus to a prescribed number of rotations of the meter, there is provided a timing mechanism or regulator operating in unison with the motor 17, but adapted to open the motor circuit when a predetermined number of revolutions of the meter has been effected. While such regulator might be located in close proximity to the meter, as in our prior application referred to, or closely associated with the motor if so desired, it has been in the present instance located on top of the apparatus and is driven from the power shaft 14. To this end, the jack shaft 20, which is mounted in suitable bearings on an extension or shelf 34, projecting from the top frame of the reservoir or container 1, carries a worm 36, meshing with a worm wheel 37, forming the initial element of the regulator. This worm wheel 37 is mounted for rotation upon a vertically disposed shaft or stud 38, carried by an oscillatory arm 39, pivoted at 40 on top of the shelf like projection 34, of the frame of the apparatus. The oscillatory arm 39, is provided with lateral ears to accommodate an arcuate slot 41, through which engages a clamp screw 42.

The adjustability of the swinging arm 39, which may be engaged in different positions by the clamp screw 42, is to accommodate worm wheels 37 of different diameters or containing different numbers of teeth for operative engagement with the same driving worm 36. Thus by providing a worm gear 37, having one more tooth or one less tooth, in its periphery, the regulator may be driven slightly slower or faster as may be required, and consequently more or less commodity will be delivered for each cycle of operation. This adjustment may be necessary to accommodate the apparatus to commodities of different densities. For instance, if it is desired to deliver at each cycle of operation, one pound of a heavy grease, a smaller worm gear may be required than to deliver one pound of a light grease. In changing from one character of commodity to another, a test run

may be made and accurately weighed to determine whether a longer or shorter cycle of operation is necessary to feed the required quantity. The worm gear 37 rotates loosely upon the stud 38, and is provided with an upwardly directed hub portion 43, within the hub 44 of a housing 45 stationarily supported upon the apparatus the wall of which forms one terminal of a make and break switch in the motor control circuit. The hub 43 of the worm gear 37 is insulated from the housing 45, by an interposed sleeve 46 of insulating material. The wheel 37 is further preferably recessed for a collar 48, of insulating material, such as fiber, upon which the end of the hub 44 abuts. Surrounding the stud 38, immediately above the hub 43 of the worm gear, is a fiber disc or collar 49, operatively engaged with the worm gear 37, by means of a stud or pin 50, and in turn engaged with a rotating arm 51, by means of a second stud or pin 52. A disc of fiber or insulating material 53 is located in the bottom of the housing 45, beneath the arm 51. The construction is such that the housing 45 is entirely insulated from the arm 51, or any of its connecting parts. The housing 45 is held stationary, by any suitable connection, 45' with the frame of the apparatus, while the arm 51 rotates within such housing, in unison with the worm gear 37, but normally insulated from the housing.

The circular wall of the housing 45 is formed with a series of spaced openings or notches 54, affording there between a series of spaced contact segments which are electrically connected into the control circuit. There may be only one of these openings or notches, in which event, the regulator arm 51 will make a complete rotation at each cycle of operation, or as shown in the drawings, there may be a plurality of notches or recesses 54 affording a series of contact segments with which the motor controlled circuit is successively closed.

The rotating arm 51 carries a spring actuated contact finger 55, pivoted at 56 to said arm 51 with which it is also electrically connected, and normally actuated into wiping engagement with the segment formed by the notched wall of the housing 45 by the spring 57. This finger 55 forms one terminal of a make and break switch the opposite terminal of which may be any one of the segments of the wall housing 45 is formed by the notches or recesses 54. The finger 55 is also provided with a stop stud 58 engaging a projection or stud 59, to limit the throw of the finger 55 under the influence of the spring 57 when such finger passes off of the arcuate wall of the housing into one of the notches 54. This wipe finger 55 by its engagement with the arcuate wall of the housing 45, completes the motor circuit and when it passes off such segmental wall into one of the openings 54,

its sudden advance movement under the influence of the spring serves to quickly break the contact with a snap off movement, thereby minimizing any arcing and opening the motor circuit, quickly and effectively. The 5 rotating arm 51 is held in engagement with the driving gear by means of a tension spring 51', abutting at its lower end upon the arm 51, and at its upper end seated within an 10 overhanging cap 60. The regulator or timer is preferably covered by a disc 61 of glass or other transparent material held in place by a flanged collar 62. This regulator is included in the motor circuit, by grounding one 15 side of the motor upon the frame of the apparatus, or otherwise connecting it electrically with the rotating arm 51. One side of the current supply circuit is then connected with the motor and the other side with the housing 20 45, so that a circuit is completed by the wiping contact with the finger 55, with the segmental wall of the housing 45 as the arm 51 is rotated. This connection will be clear from an examination of Fig. 5, wherein the electrical 25 circuits are shown. It is obvious that so long as the wipe finger is in engagement with the segmental wall of the housing 45, current will be supplied to the motor and the apparatus will continue in operation. However, 30 as the wipe finger approaches one of the notches 54, and is actuated by its spring to break the electrical circuit, the motor will be brought to rest. In order to initiate the 35 operation of the apparatus, it is necessary to bridge this open contact between the wipe finger 55, and the housing 45. This in the present instance is effected by means of a push button upon the discharge nozzle of the conduit 23. At the extremity of the conduit 40 there is provided a nozzle 63, preferably having therein a cut-off valve 64. Located on the side of the nozzle 63, adjacent to the cut-off valve is an electrical push button 65, from which conductor wires lead, preferably 45 through the discharge conduit to the apparatus and thence across the gap afforded by the wipe finger 55, and the contact wall of the housing 45. This connection is shown diagrammatically in Fig. 5, where it is obvious 50 that by closing the push button 65, momentarily, the motor will be actuated to advance the wipe finger 55 until it engages the segmental wall of the housing 45 whereupon the push button 65 may be released, and the motor will continue its operation, until the next notch or opening 54 is engaged by the contact finger 55.

The purpose of mounting this control switch 65 upon the discharge nozzle, is to enable the apparatus to be controlled by a single operator. The discharge conduit 23, may be of any suitable length, and whatever its 55 length may be, the operator who holds the discharge nozzle and therefore observes the flow of the commodity, has absolute control

of the starting of the apparatus. The apparatus when once started will continue its operation until the predetermined quantity is delivered. This quantity is preferably predetermined in pound or pint lots. That is to say, the apparatus is so designed and the gear ratios of the worm drives 36 and 37, so proportioned that one pound or one pint of commodity will be delivered while the arm 51 rotates to carry its wipe finger 55 from one opening 54 to the next one. 70

As a matter of safety, the valve 63, upon the nozzle is preferably so interconnected with the switch button 65 that the latter cannot be operated until the valve is opened. 80 This interlocking connection may be of any suitable type, such as will compel the opening of the valve, in order to permit the operation of the push button.

The top of the container or reservoir 1 is provided with a lid 66 having an upstanding hollow standard 67, provided with a lateral access opening 68, into which the end of the nozzle may be inserted when not in use. To this end the nozzle is provided with a pin 90 or finger 69, by which it may be operatively engaged in the opening 68, by hanging it therein. 95

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages. 100

While in order to comply with the patent statute the invention has been described in language more or less specific as to structural features, it is to be understood that the invention is not limited to the specific details shown, but that the means and construction herein disclosed comprises the preferred form of several modes of putting the invention into effect, and the invention is therefore claimed in any of its forms or modifications within the legitimate and valid scope of the appended claims. 110

Having thus described our invention, we claim:

1. In a dispensing apparatus of the character described, a reservoir, motor actuated ejector means, a discharge conduit, and a motor control switch located in proximity to the discharge end of said conduit for initiating the operation of the motor with means for maintaining the motor in operation independent of the said switch until a predetermined quantity of commodity is discharged through said conduit. 120
2. In a dispensing apparatus of the character described, a reservoir, motor actuated commodity ejecting means, a discharge con- 130

duit, means for automatically arresting the motor driven ejector means after a predetermined period of operation and a starting switch for said motor carried by the discharge conduit in proximity to the outlet thereof and means for maintaining the motor in operation subsequent to the opening of said starting switch until a predetermined cycle of operation is completed.

10 3. In a dispensing apparatus of the character described, a reservoir, commodity ejector means, a discharge conduit, and means carried adjacent to the discharge end of the conduit for setting the ejector means in operation and means for continuing the actuation of the ejector means independent of such starting means until the predetermined quantity of commodity has been discharged and to thereupon arrest the operation of said 20 ejector means.

4. In a dispensing apparatus of the character described, a reservoir, commodity ejector means, a discharge conduit, and initiating means for the ejector located adjacent to the discharge end of the conduit whereby the apparatus can be governed by an operator at the point of discharge and means for continuing the operation of the ejector means throughout a predetermined cycle of operation 30 independent of the starting means.

5. In a dispensing apparatus of the character described, a reservoir, ejector means, an electric motor actuating the ejector, an automatic timer adapted to open the motor circuit at the end of a predetermined cycle of operations, a discharge conduit, and a switch located in proximity to the discharge end of the conduit by which the motor circuit may be closed independent of said timer.

40 6. In a dispensing apparatus of the character described, a reservoir, intermittently actuated ejector means, a discharge conduit, and distant starting means for the ejector located adjacent to the end of the discharge conduit and means for continuing the operation of the ejector means through a predetermined cycle of operation.

7. In a dispensing apparatus of the character described, a reservoir, electrically actuated ejector means, a discharge conduit, and a control circuit for the electrically actuated ejector means, extending within the discharge conduit, a starting switch adjacent the discharge end of the conduit and an 50 automatic circuit breaker in said circuit by which the circuit is automatically opened after a predetermined period of operation, initiated by the starting switch.

8. An apparatus of the character described, including a reservoir, electrically operated ejector means, and a conduit, characterized by a timer for said electrically actuated ejector means adapted to arrest the ejector means after a predetermined cycle of 65 operation, comprising a contact face, a

spring actuated contact finger engaging the contact face, a movable carrier for the finger, said carrier and contact face being relatively movable in relation one with the other, and in unison with the actuation of the ejector means, whereby said finger will disengage the contact face with a snap off action at the end of a predetermined cycle of operation of the ejector means, and a starting switch bridged across the timer parts for initially 70 actuating the ejector independent of the engagement of the contact finger and face.

9. The combination with a reservoir, electrically actuated ejector means, and a discharge nozzle, characterized by a timer adapted to arrest the ejector at the end of a predetermined cycle of operations, including a head having a plurality of spaced contact segments, a wipe finger engaging said contacts successively under spring tension, a carrier for the finger, said carrier and segments being relatively movable in unison with the ejector means, whereby said finger will disengage a segment with a snap off action at the end of a predetermined cycle of operation and a starting switch bridged across said carrier and segments for initiating the operation of the apparatus.

10. The combination with a reservoir, electrically actuated ejector means and a discharge nozzle, characterized by a timer adapted to arrest the ejector at the end of a predetermined cycle of operations, comprising two relatively movable contact members actuated in unison with the ejector and moving out of operative engagement one with the other at the end of a predetermined cycle of ejector operation, and a starting switch bridged across said relatively movable contact member for initiating the operation of the apparatus.

11. The combination with a reservoir, electrically actuated ejector means, and a discharge nozzle, characterized by a timer adapted to arrest the ejector at the end of a predetermined cycle of operations, comprising two relatively movable contact members spring pressed into engagement with each other and relatively moved in unison with the actuation of the ejector means, said contact members being adapted to spring apart at the end of a predetermined cycle of operation, and a starting switch bridged across the contact members for initiating the operation of the apparatus.

12. In an apparatus of the character described, the combination with a reservoir, ejector means and a discharge conduit, characterized by governor means for arresting the operation of the ejector at the termination of a predetermined cycle of operation, operative connections for actuating the governor in unison with the ejector means including a pair of intermeshing gears the axes of rotation of which are relatively ad-

justable in relation one with the other to enable the substitution of gear members of different proportions to vary the length of such cycle of operation of the ejector.

5 13. In an apparatus of the character described, the combination with a reservoir, ejector means and a discharge conduit, characterized by governor means for arresting the operation of the ejector at the termination of a predetermined cycle of operation, a swinging carrier for said governor means, a driven gear therefor upon said carrier, a driving gear operatively connected with the ejector means for unison operation, said driving and driven gears being intermeshed by the swinging adjustment of said carrier, the adjustment of said carrier permitting the employment of gears of different proportions as the driven gear to vary the extent of the predetermined cycle of operation.

10 14. In an apparatus of the character described, the combination with a reservoir, ejector means and a discharge conduit, characterized by governor means for arresting the operation of the ejector at the termination of a predetermined cycle of operation, operative connections for actuating the governor means in unison with the ejector means, the relative speeds of operation of the governor means and the ejector means being variable at will to proportionately vary the predetermined cycle of operation.

15 15. In an apparatus of the character described, the combination with a reservoir, ejector means and a discharge conduit, characterized by governor means for arresting the operation of the ejector at the termination of a predetermined cycle of operation, and a variable driving connection between the governor means and the ejector the governor and ejector means being capable of operation at different relative rates of speed to vary the extent of the predetermined cycle of operation.

20 16. In an apparatus of the character described, the combination with a reservoir, electrically propelled ejector means and a discharge conduit, characterized by a timer switch adapted to disconnect the actuating circuit of the electrically propelled ejector at the limit of a predetermined cycle of operation, an adjustable mounting for said timer switch, said switch means operable in unison with the operation of the ejector means in various positions of adjustment of the carrier at different relative speeds whereby the extent of said predetermined cycle of operation is varied according to the relative positions of the carrier.

25 17. In an apparatus of the character described, the combination with a reservoir, ejector means, and a discharge conduit, characterized by a meter operating in unison with the ejector means including a circular housing, a rotor eccentrically positioned therein,

a radially disposed vane carried by the rotor and engaging the wall of the circular housing, and means for interlocking the vane with the housing during its movement therein to maintain their operative adjustment during their period of active operation said ejector means serving as a force feed device for said meter to insure operation of the meter at maximum capacity.

30 18. In an apparatus of the character described, the combination with ejector means and a discharge conduit of a meter therein receiving the ejected commodity under pressure from said ejector means comprising a circular housing, a rotor eccentrically positioned therein and a radially disposed vane carried by the rotor and sweeping the circular walls of the housing, of a guide rib upon the head of the housing engaging in a corresponding recess in the sweep vane during the operative movement thereof to maintain the relative relation of the vane with the circular wall of the housing to insure maximum capacity operation of the meter.

35 19. In an apparatus of the character described, the combination with ejector means and a discharge conduit, of a meter therein supplied under pressure by the ejector means comprising a circular housing, a rotor eccentrically positioned therein, and a radially disposed vane carried by the rotor and sweeping the circular walls of the housing, of a splined connection between the vanes and housing to maintain the operative relation of the vane with the housing during the relative movement thereof in its operative stroke said ejector means serving as a force feed device to insure maximum capacity operation of the meter.

40 In testimony whereof, we have hereunto set our hands this 2nd day of May, A. D. 1922.

JACOB BALDNER.
GEORGE BALDNER.
